(57) **CLAIM**

The ornamental design for a display screen with a graphical user interface, as shown and described.

DESCRIPTION

FIG. 1 is a front view of a display screen with a graphical user interface, showing our new design, according to a first embodiment thereof; and,

FIG. 2 is a front view of a display screen with a graphical user interface, showing our new design, according to a second embodiment thereof.

In FIGS. 1 and 2, different stippling patterns indicate different regions of contrasting appearance.

The innermost broken line rectangle shows the display screen and the remaining broken lines depict the environment of a device and forms no part of the claim.
